UNITED STATES PATENT OFFICE.

WILLIAM A. KELSEY, OF MERIDEN, CONNECTICUT.

DESIGN FOR A CARD.

SPECIFICATION forming part of Design No. 17,308, dated May 3, 1887.

Application filed March 5, 1887. Serial No. 229,879. Term of patent 3½ years.

To all whom it may concern:

Be it known that I, WILLIAM A. KELSEY, a citizen of the United States, and a resident of Meriden, in the county of New Haven and State of Connecticut, have invented certain new and useful Improvements in Designs for Cards; and I do hereby declare that the following is a full, clear, and exact description of the invention, which will enable others skilled in the art to 10 which it appertains to make and use the same, reference being had to the accompanying drawing, which forms a part of this specification, and which is a representation of a card of my design.

15 My design relates to cards and similar stationery; and it consists in an ornamental serrated outline given to the card, as hereinafter more fully described and claimed.

In the drawing the card is shown having the 20 upper and lower edge formed with each two segmental notches, 1, formed with a rather large radius, and the spaces at the middles of the edges between the large notches or serrations are formed with each three smaller notches or serrations, 2, segmental in shape 25 and made with a comparatively very much smaller radius.

The ends of the card are formed with two

large segmental notches, 3, made with a radius still larger than the radius of the segmental lines of the upper and lower edges, and the corners of the card are formed with two smaller segmental notches or lines, 4, at the ends of the large segmental notches or lines, and a tongue, 5, between the said small segmental lines, having a segmental notch or concave line, 6, in its end.

Having thus described the design, I claim and desire to secure by Letters Patent of the United States—

The design for a card, consisting of an upper and lower edge having each two concave large segmental notches separated by three smaller segmental concave notches or serrations, large segmental and concave notches in the ends, 45 and corners formed with two smaller segmental notches forming a tongue between them having a segmental notch in its end, as shown and described.

In testimony that I claim the foregoing as 50 my own I have hereunto affixed my signature in presence of two witnesses.

WILLIAM A. KELSEY.
